FOREIGN PATENT DOCUMENTS

CN 3166356 * 11/2000
GB 9008166888-0001 * 9/2020*Primary Examiner* — Paula Allen Greene(74) *Attorney, Agent, or Firm* — Westbridge IP LLC(57) **CLAIM**

The ornamental design for a handheld microphone boom pole, as shown and described.

DESCRIPTION

FIG. 1 is a top and front perspective view of a handheld microphone boom pole showing our new design;

FIG. 2 is a bottom and rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partial enlarged view taken from square 9 in FIG. 1;

FIG. 10 is a partial enlarged view taken from square 10 in FIG. 2;

FIG. 11 is a partial enlarged view taken from square 11 in FIG. 2;

FIG. 12 is a top and front perspective view thereof in another position;

FIG. 13 is a partial enlarged view taken from square 13 in FIG. 12;

FIG. 14 is an enlarged view of FIG. 7; and,

FIG. 15 is an enlarged view of FIG. 8.

The dash-dash broken lines in the drawings depict the portions of the handheld microphone boom pole which form no part of the claimed design.

The dot dash broken line around portions of the handheld microphone boom pole in FIGS. 1, 2 and 12 and illustrated in the enlarged views of FIGS. 9 through 13 form no part of the claimed design.
